AUTOMATIC VOLUME CONTROL

Rene A. Braden, Collingswood, N. J., assignor to
 Radio Corporation of America, a corporation
 of Delaware

Application June 26, 1933, Serial No. 677,614

7 Claims. (Cl. 250—20)

My present invention relates to high frequency amplifier gain control circuits, and more particularly to an arrangement for automatically regulating the gain of radio frequency amplifier circuits.

In all automatic gain control arrangements for the high frequency amplifier circuits of radio receivers there exists an ideal automatic volume control action which is sought to be attained.

10 Briefly, it may be stated that this ideal is to increase the "stiffness" of the automatic volume control action as economically as possible. Various devices and arrangements have been utilized to approach this ideal operation.

15 It may be stated that it is one of the main objects of my present invention to provide an automatic volume control arrangement for a radio receiver wherein the stiffness of automatic volume control is secured at substantially negligible expense by employing, in conjunction with the usual automatic volume control tube, an element capable of maintaining the voltage drop across it substantially constant with increasing flow of current through this element.

20 Another important object of the present invention is to provide in an automatic volume control network for a high frequency amplifier an economical form of voltage regulator, the latter consisting of a carborundum material, and being capable of having the voltage drop across itself substantially constant over a wide range of current variation.

25 Still another object of the present invention is to provide in combination with an automatic volume control arrangement adapted to control the potential of a high frequency amplifier control grid, or screen grid, and which automatic volume control arrangement includes a volume control rectifier having its control grid connected to the control grid of an amplifier to be controlled, a voltage regulator element composed substantially of carborundum, the voltage regulator element being connected in the anode circuit of the volume control rectifier.

30 35 40 45 50 Still other objects of the present invention are to improve generally the simplicity and efficiency of automatic gain control networks of radio receivers, and particularly to provide such a network which is not only reliable in operation, but economically manufactured and assembled in a radio receiver.

The novel features which I believe to be characteristic of my invention are set forth in particularity in the appended claims, the invention itself, however, as to both its organization and

method of operation will best be understood by reference to the following description taken in connection with the drawing in which I have indicated diagrammatically several circuit organizations whereby my invention may be carried into effect.

In the drawing, Fig. 1 diagrammatically shows a receiving circuit embodying one form of the invention,

Fig. 2 shows a modified application of the invention.

Referring now to the accompanying drawing, wherein like reference characters in the different figures represent similar circuit elements, there is shown in Fig. 1 a radio receiver, of the super-heterodyne type, which embodies an automatic gain control network. In general, the automatic gain control arrangement shown in Fig. 1 follows the arrangement disclosed and claimed by K. A. Chittick and W. L. Carlson in application Serial No. 642,544, filed November 14, 1932. For the purpose of simplification of description however, the aforementioned arrangement in the said co-pending application has been simplified. The source of signals 1 may comprise the usual grounded antenna circuit, and the source is shown coupled, as at M, to the input electrodes of a radio frequency amplifier tube 2, the latter being of the screen grid type, and including an indirectly heated cathode. The variable tuning condenser 3 is connected across the coil 4, and the rotor plates of the condenser 3 are shown grounded, the lead 3' of the cathode of tube 2 being connected to point b on resistor P.

The anode circuit of the amplifier tube 2 is coupled, as at M₁, to the tunable signal input circuit 6 of the succeeding combined detector-oscillator. This signal input circuit includes the variable tuning condenser 7, and a dotted line 8 between the rotor plates of condensers 3 and 7 designates the well known uni-control tuning means. While a combined detector-oscillator circuit is shown in Fig. 1, it is to be clearly understood that separate tubes may be employed in distinct local oscillator and first detector stages, in a manner well known to those skilled in the art. Since the details of the detector oscillator circuit are not necessary to a proper understanding of the present invention, this circuit is conventionally shown.

50 55 The intermediate frequency output of the detector-oscillator is impressed across the input electrodes of the intermediate frequency amplifier tube 2', the latter being of the same type as the tube 2. The coupling network M₂ between the

combined detector-oscillator and the input electrodes of tube 2' includes the usual coupled resonant circuits, both being fixedly tuned to the operating intermediate frequency. The cathode lead 3" of tube 2' is connected to point c on resistor P. The customary second detector circuit follows the intermediate frequency amplifier tube 2', and the output of the second detector is impressed upon an audio frequency amplifier, not shown to preserve simplicity of description. The coupling network M₃ between the tube 2' and the second detector is of the same type as the coupling network M₂.

The automatic volume control network comprises a screen grid tube 9, of the indirectly heated cathode type, the control grid of the tube 9 being connected to the control grid of tube 2' through a path which comprises the lead 10. In order to furnish proper negative bias for the control grid of tube 9, the cathode of the tube is connected by lead 11 to point d on resistor P.

The anode of tube 9 is connected to the source of positive potential B (this source not being shown) through a resistor 12 having a high resistive magnitude. The anode side of the resistor 12 is connected to ground through a series path including the voltage regulator element 13 and the resistor 14. The resistor P is connected in parallel with the last named series path 13, 14.

The resistor 14 has a low resistive magnitude, and the voltage regulator element 13 can be said to have a falling resistance characteristic since R decreases as I increases. To secure automatic gain control of the radio frequency amplifier and intermediate frequency amplifier, the high potential side of resistor 14 is connected through a lead 15 to the control grid circuits of tubes 2 and 2'. The control grid of tube 2 is connected to the lead 15 through a path which includes the lead 16. The resistor 17 has a high resistance and is connected to ground from lead 15. The lead 16 is connected to a point e on resistor 17 such that the bias control action on the control grids of tubes 2 and 2' is graded. That is, the control starts on all tubes at the same time, but the amount of control is graded so that one tube gets more than the other. In order to adjust the level at which automatic volume control action is to commence, an adjustable slider 19 is provided.

The voltage regulator element 13 consists substantially of a carborundum disc. The opposite faces of the disc are provided with metallic electrodes 13', and these electrodes are usually provided on the opposite faces of the disc by spraying discs of metal on these faces. The connections from the anode of tube 9 and the ungrounded side of the resistor 14 are made to these metallic discs 13'. The property of the voltage regulator element is to maintain the voltage drop across it, when current flows therethrough, substantially constant. Reference is made to page 93 of an article entitled "Thyrite" appearing in the General Electric Review for February, 1930, for a description of the electrical characteristics of the voltage regulator element 13.

The operation of the invention will now be clearly understood in view of the foregoing description. The automatic volume control network functions in the usual manner, the potential drop across the control grid bias resistor 14 varying with the intensity of the signal energy impressed upon the control grid of tube 9. An increase in signal energy impressed on the control grid of tube 9 results in the point on resistor 14 to which the slider 19 is connected becoming less positive

with respect to ground, or negative end of plate supply voltage. This results in the control grids of tubes 2 and 2' becoming more negative with respect to their associated cathodes, the latter being positive with respect to ground. Thus, the gain of the stages including tubes 2 and 2' is reduced. With decreasing signal voltage, the reverse action takes place.

If the voltage regulator element 13 were not used in series with the control bias resistor 14, but a resistor substituted for this voltage regulator element, there would be secured a lesser percentage drop across the resistor 14 for a given signal current increase. In other words, in view of the fact that the voltage drop across the element 13 is substantially constant over a wide range of current variation, there is secured a larger percentage drop across the control bias resistor 14 for a given signal current increase, than if the element 13 were omitted and replaced by a resistor. Hence, the stiffness of the automatic volume control action has been substantially increased, and in an economical manner since the cost of the element 13 is negligible compared to that of the customary circuit elements utilized.

In Fig. 2 is shown a modification of the invention wherein the screen grid potentials of the radio frequency amplifier tube 2 and the intermediate frequency amplifier tube 2' are automatically controlled from the volume control tube 9. The volume control rectifier 9 has its anode, in this case, connected by the lead 15' to the screen grid electrodes of tubes 2 and 2'. In this application of the invention when the intensity of the signal energy applied to the control grid of tube 9 increases, the control potential applied to the screen grids of tubes 2 and 2' through lead 15' decreases.

A neon tube could be used in place of element 13. When such a neon lamp is placed in series with the resistor 14, the function of the lamp is to maintain a constant voltage at one point in the circuit so that all of the variation voltage appears across the resistor. While I have indicated and described several systems for carrying my invention into effect it will be apparent to one skilled in the art that my invention is by no means limited to the particular organizations shown and described, but that many modifications may be made without departing from the scope of my invention as set forth in the appended claims.

What I claim is:

1. In an automatic gain control arrangement for a radio receiver, an amplifier to be controlled as to gain, a rectifier connected to the input circuit of the amplifier, a path in the output circuit of the rectifier including a bias control resistor, a direct current connection from said resistor to an input electrode of said amplifier, said path including an additional element composed of silicon carbide and having an electrical characteristic such that the bias control variation voltage takes place across said resistor.

2. In an automatic gain control arrangement for a radio receiver, an amplifier to be controlled as to gain, a rectifier connected to the amplifier, a path in the output circuit of the rectifier including a bias control resistor, a direct current connection from said resistor to a gain control electrode of said amplifier, said path including an additional element consisting substantially of carborundum and having an electrical characteristic such that the bias control variation voltage takes place across said resistor.

3. In an automatic gain control arrangement

for a radio receiver, an amplifier to be controlled as to gain, a rectifier connected to the amplifier, a path in the output circuit of the rectifier including a bias control resistor, a direct current connection from said resistor to a cold gain control electrode of said amplifier, said path including an additional element composed substantially of silicon carbide and having an electrical characteristic such that the resistance of the element decreases as the current flow therethrough increases whereby the bias control variation voltage takes place across said resistor.

4. In an automatic gain control arrangement for a radio receiver, an amplifier to be controlled as to gain, a rectifier connected to the amplifier, a path in the output circuit of the rectifier including a bias control resistor, a direct current connection from said resistor to a positive cold electrode of said amplifier, said path including an additional element composed of carborundum having an electrical characteristic such that the bias control variation voltage takes place across said resistor.

5. In a signaling system of the type including a signal transmission tube, an electron discharge tube having a signal input circuit and an impedance in its space current path, and a direct current connection between a point on said impedance and an electrode of said transmission tube

whereby the transmission of signals through the first tube is a function of a gain control voltage developed across the impedance, and a device in the space current path of said second tube having a resistance characteristic such that the voltage developed thereacross by the space current flow is substantially constant over a wide range of current variation whereby said gain control voltage is developed substantially across the said impedance.

6. In a system as defined in claim 5, said device being arranged in series with said impedance, and said electrode being the signal control grid.

7. In a signaling system of the type including a signal transmission tube, an electron discharge tube having a signal input circuit and an impedance in its space current path, and a direct current connection between a point on said impedance and an electrode of said transmission tube whereby the transmission of signals through the first tube is a function of the voltage developed across the impedance, a device in the space current path of said second tube having a resistance characteristic such that the voltage developed thereacross by the space current flow is substantially constant over a wide range of current variation, said device consisting of an element composed substantially of silicon carbide.
